J. Harriman

Cook Stove.

Patented Mar. 31, 1834.

John Harriman

Mar 31 1834

8127X

The Schedule referred to in these Letters Patent and, making part of the same containing a description, in the words of the said John Harriman, briefly of his improvement in the manner of constructing Stoves for cooking and for other purposes.

To all whom it may concern. Be it known that John Harriman of Flowerhill in the County of Essex and State of Massachusetts have invented certain improvements in the manner of constructing Stoves for cooking and for other purposes, and that the following is a full and exact description thereof. The principle part of the body of this stove is to be made of Cast iron. The bottom plate forms the cap, the bottom of the fire place and of an oven situated behind it. The fire place is like that in many other stoves, being a deep open stove and having double doors in front, which may be closed when requisite. In the upper plate of the fire place I usually make three perforations for the reception of cooking utensils, the middle one large and furnished with concentric, circular rings of different sizes to adapt it to different kinds of vessels. Near to the back end of this plate I make two other openings which may be either round or oval, and to give sufficient room for these, I pull out the said top plate and also the side plates of the fire place giving to it a curved form which is at the same time both ornamental and convenient. There may, if desired, be other openings in the top, but these are all that I deem essential.

The oven is situated behind the fire place and is ^{in the form} made of a rectangular box, one side of which is against the back of the stove. The oven has a door or door ^{it} ornamental, and is framed with outer plates of cast iron and inner plates of sheet iron. This latter part is made

made in apparatus as to admit of top, so that it can be drawn out whenever it requires to be repaired or renewed. It is made so much smaller than the outer top, as to admit a space between the top, bottom and sides, through which the heated air and smoke are to pass in their passage to the pipe. These escape from the fire through a throat or opening in the upper part of the stove back and then pass down and under the oven, thence often ascending to the top, where there is an opening for a stove pipe. This opening is surrounded by a partition on the top of the oven, to prevent the heated air from passing over it with outgoing down and around it. In this partition there are valves which may be opened when it is wished to direct any part of the current over the oven. It is usual sometimes to cover the top of the inner portion of the oven with cast iron plate, should the intensity of the heat render it necessary.

Instead of making openings directly through the top plate of the oven for receiving cooking apparatus, I make a rectangular opening, the length of which may be twice as great as its breadth, and adapt stove pipe fitting made to this opening. The plate which is to cover it when not wanted, to be partially open, perforate so as smaller cooking vessels when required. By this arrangement holding plates for warming for cooking meat or other articles by boiling as well as roasting, baking, drying and broiling, may all be carried on together or any desired number of them may be performed separately.

What I claim as my invention and wish to secure by Letters Patent is the form given to the body of the stove for the purpose of receiving the two smaller openings for vessels near the back and side doors, thus making the rectangular opening in the outer top plate of the oven in the manner and for the purposes set forth. The making the oven back, door and so as to draw out and the particular arrangement of the parts for attaining this result.
